UNITED STATES PATENT OFFICE.

FRANK J. HILL, OF SULPHUR, LOUISIANA.

METHOD OF AND APPARATUS FOR TREATING AND HANDLING SULFUR.

1,397,099.

Specification of Letters Patent. Patented Nov. 15, 1921.

Application filed July 6, 1920. Serial No. 394,877.

To all whom it may concern:

Be it known that I, FRANK J. HILL, a citizen of the United States, and a resident of Sulphur, in the parish of Calcasieu and 5 State of Louisiana, have made certain new and useful Improvements in Methods of and Apparatus for Treating and Handling Sulfur, of which the following is a specification.

This invention relates to a method of and 0 apparatus for treating and handling sulfur.

Heretofore in the commercial production of sulfur the sulfur has been melted underground and forced up by compressed air to the pumping station and then through 5 suitable conduits to large bins where it is allowed to stand and congeal. The latter features of this process have many inherent disadvantages in that they necessitate the mining of the sulfur many months in advance in order that it may cool before it can be blasted and shipped. This requires the operation of a large number of batteries and wells in order to have available sulfur at all times, and this as well as the construction and maintenance of the bins make this process burdensome and expensive.

One of the principal objects of the present invention is to provide for the treatment and handling of the sulfur in the molten condition in which it is delivered from the well to render it susceptible of immediate transportation and available for immediate use, thus avoiding the expense and inconvenience, of the long delay, of the construction and maintenance of the bins, or of the operation of an excessive number of wells, or in a word, to avoid or overcome all the difficulties and disadvantages of these features of the present methods.

Other objects and advantages reside in the certain novel features of the construction, arrangement and combination of parts, which will be hereinafter more fully described, and particularly pointed out in the appended claims, reference being had to the accompanying drawing forming part of this specification, and in which:

Figure 1 is a side elevational view of the apparatus embodying my invention.

Fig. 2 is a plan view thereof.

Fig. 3 is a transverse vertical section.

Fig. 4 is a side elevational view of the sulfur nozzle, water drum and steam drum assembled,

Fig. 5 is a transverse vertical sectional 55 view on line 5—5 of Fig. 3.

Fig. 6 is an end elevational view of the steam drum.

Fig. 7 is a transverse vertical sectional 60 view on line 7—7 of Fig. 3.

Referring to the drawings it will be seen that the apparatus embodying my invention is preferably mounted upon a suitable trestle work or similar supporting structure designated at 10. The apparatus consists of a 65 steam jacketed casing 11 built up of a plurality of sections 12, each section preferably comprising spaced shells 12^a of metallic construction of elongated cylindrical form. One end of the casing 11 is closed by a suitable 70 head 13 and the other end is open as at 14 to constitute the discharge end of the casing. A conduit 15 for the molten sulfur leads from the well and extends through and axially of the casing to adjacent the open 75 end 14 thereof. The inner end of the conduit within the casing carries a steam nozzle 16, which is of tubular construction having its outer end closed by a cap plate 17 and having its inner end open and coupled to the 80 conduit 15. The periphery of the tubular nozzle is provided with a plurality or series of spirally extending slots 18 which constitute discharge openings for the molten sulfur and serve to break up into relatively 85 small particles, the molten sulfur projected therethrough.

A water drum 19 is arranged on the conduit 15 and concentric thereto. The water drum is disposed adjacent the nozzle 16 of 90 the sulfur conduit and as seen in Fig. 5, the head 19^a of the water drum adjacent the nozzle is provided with a series of alternate circumferentially and radially extending slots 20 which constitute discharge orifices 95 for spraying the water from the water drum on to the particles of the molten sulfur discharged from the nozzle 16. The heads 19^a of the water drum are each provided with collars 19^b having threaded engagement as 100 at 19^c, with the periphery of the sulfur conduit. The collar of the head adjacent the nozzle 16, preferably, has threaded engagement also with the nozzle 16 as at 19^d and thus serves to couple the nozzle to the sulfur 105 conduit. A water supply pipe 21 extends through the steam jacketed casing 11 and delivers or supplies water under pressure to

the water drum 19. The juncture of the pipe 21 and the shells 12^a of the casing is suitably reinforced and packed as at 21^a.

5 A steam drum 22 is arranged adjacent the rear of the water drum and is mounted upon a sulfur conduit 15, the heads 22^a of the water drum having for this purpose annular collars 22^b having threaded engagement as at 22^c with the periphery of the 10 conduit 15. The head of the steam drum adjacent to the water drum is provided with an inner and outer circular series of radially extending jet openings 23 (see Fig. 6) from which steam jets are delivered.

15 Means is provided for supplying steam for the heating and blowing purposes and consists of a main steam pipe 24 and an auxiliary steam pipe 25 delivering to the main steam pipe.

20 The auxiliary steam pipe 25 extends through the bushing 26 threaded in the T coupling 27 embodied in the sulfur conduit 15 and the auxiliary steam pipe 25 is itself connected to the main steam pipe 24 by 25 means of a T coupling 28. The main steam pipe 24 extends axially entirely through the sulfur conduit and then leads by elbows 29 and short pipes 30 to the steam jacket of the casing 11. A short pipe 31 delivers the 30 steam from the steam jacket to the steam drum as clearly shown in Fig. 3. A valve 32 is incorporated in the water pipe 21 and a valve 33 is incorporated in the steam pipe 25 to control the flow through said pipes.

35 In operation the molten sulfur flows through the sulfur conduit 15, and is discharged through the nozzle 16 thereof. The nozzle 16 breaks the sulfur up into fine particles and while in this state immediately 40 after being discharged from the nozzle, or rather, as it is discharged from the nozzle, it is subjected to a spray of water from the orifices of the water drum. The water acting upon the molten sulfur granulates the 45 same and the steam jets of the steam drum project or discharge the granulated sulfur through the open end of the casing. The sulfur does not adhere to the steam casing in view of the steam jacket which maintains 50 the inner surface of the same heated at all time to preclude any adhering or clogging of the sulfur.

The granulated sulfur delivered from the discharge or open end 14 of the casing is 55 available for immediate use or for immediate transportation. Any suitable conveying or handling means such as for instance shown diagrammatically at C, is provided to receive and transfer the granulated sulfur 60 to a freight car F or storage structure if desired.

The apparatus embodying my invention has been hereinabove described, but it will be understood that my invention also involves a method in that it contemplates in 65

the first instance the breaking up of the molten sulfur into relatively small particles and secondly, the spraying of the particles of the molten sulfur with water to granulate the sulfur. The sulfur is then discharged from the region in which the granulating action occurs by a jet or jets of steam. 70

I claim:—

1. In an apparatus of the character described, an elongated steam jacketed casing 75 having one end closed and the other end open, a conduit for molten sulfur extending axially of said casing to adjacent the open end thereof, a steam pipe leading axially through said conduit to the steam jacket of 80 said casing, a nozzle for the molten sulfur carried by the outer end of said conduit having a series of spiral discharge orifices, a water drum arranged on said conduit and having a series of orifices whereby the discharge of said nozzle is sprayed with water to granulate the sulfur, a steam drum having a plurality of jet openings adapted to direct jets against the granulated sulfur to discharge the same through the open end of 85 said casing, and a steam pipe from the jacket to the steam drum to supply the steam thereto.

2. In an apparatus of the character described, an elongated steam jacketed casing 95 having one end closed and the other end open, a conduit for molten sulfur extending axially of said casing to adjacent the open end thereof, a steam pipe leading axially through said conduit to the steam jacket of 100 said casing, a nozzle for the molten sulfur carried by the outer end of said conduit having a series of spiral discharge orifices, a water drum arranged on said conduit and having a series of orifices whereby the discharge of said nozzle is sprayed with water to granulate the sulfur, and a steam drum having a plurality of jet openings adapted to direct jets against the granulated sulfur to discharge the same through the open end of 105 said casing, and a steam pipe from the jacket to the steam drum to supply the steam thereto.

3. In an apparatus of the character described, an elongated steam jacketed casing having one end closed and the other end open, a conduit for molten sulfur extending axially of said casing to adjacent the open end thereof, a steam pipe leading axially through said conduit to the steam jacket of 110 said casing, a nozzle for the molten sulfur carried by the outer end of said conduit having a series of spiral discharge orifices, a water drum arranged on said conduit and having a series of orifices whereby the discharge of said nozzle is sprayed with water to granulate the sulfur.

4. In an apparatus of the character described, a steam jacketed casing, a conduit for molten sulfur extending within said casing, a nozzle for said conduit provided with spiral discharge openings, a water drum car- 115 120 125 130

- ried by said conduit and having orifices adapted to spray the molten sulfur to granulate the same, and a steam drum having a plurality of jet openings for discharging the 5 granulated sulfur from said casing.
5. In an apparatus of the character described, a casing, a steam jacket for said casing, a conduit for molten sulfur arranged within said casing, a nozzle carried by the 10 end of said conduit within said casing, a steam pipe leading through said conduit and said nozzle to said steam jacket, a water drum having a plurality of discharge orifices adjacent said nozzle to spray the molten 15 sulfur to granulate the same, a steam drum having a plurality of jet openings, and a steam pipe leading from said steam jacket to said steam drum.
6. In an apparatus of the character described, a casing, a conduit for molten sulfur arranged within said casing, a spray nozzle carried by the end of said conduit within said casing, a water drum having a plurality of discharge orifices adjacent said 20 nozzle to spray the molten sulfur to granulate the same, a steam drum having a plurality of jet openings, and means for supplying steam to said steam drum.
7. In an apparatus of the character described, a casing, a conduit for molten sulfur arranged within said casing, a spray nozzle carried by the end of said conduit within said casing, a water drum having a plurality of discharge orifices adjacent said 25 nozzle to spray the molten sulfur to granulate the same, and a steam drum having a plurality of jet openings.
8. In an apparatus of the character described, a casing, a conduit for molten sulfur arranged within said casing, a spray nozzle carried by the end of said conduit within said casing, and a water drum having a plurality of discharge orifices adjacent said nozzle to spray the molten sulfur to granulate 30 the same.
9. In an apparatus of the character described, a steam jacketed casing, a conduit for molten sulfur arranged within said casing, a spray nozzle carried by the end of said conduit within said casing, a water drum having a plurality of discharge orifices adjacent said nozzle to spray the molten sulfur to granulate 35 the same.
10. In an apparatus of the character described, a steam jacketed casing, a conduit for molten sulfur arranged within said casing, a spray nozzle carried by the end of said conduit within said casing, and a water drum having a plurality of discharge orifices adjacent said nozzle to spray the molten sulfur to granulate the same, a steam drum having a plurality of jet openings for discharging the 40 granulated sulfur from said casing.
11. In an apparatus of the character described, a steam jacketed casing, a spray nozzle for molten sulfur arranged within said casing, means for spraying the discharge of said nozzle with water to granulate the sulfur, and a steam jet for discharging a granulated sulfur from said casing.
12. In an apparatus of the character described, a spray nozzle for the molten sulfur, means for spraying the discharge of said nozzle with water to granulate the sulfur, and a steam jet for discharging the granulated sulfur.
13. In an apparatus of the character described, a spray nozzle for the molten sulfur, and means for spraying the discharge of said nozzle with water to granulate the sulfur.
14. In an apparatus of the character described, a spray nozzle for the molten sulfur, means for spraying the discharge of said nozzle with water to granulate the sulfur, and a steam jet for discharging the granulated sulfur, said nozzle, said spraying means and said steam jet being arranged in tandem.
15. In an apparatus of the character described, a spray nozzle for the molten sulfur, and means for spraying the discharge of said nozzle with water to granulate the sulfur, said nozzle and said spraying means being arranged in tandem.
16. The method of treating sulfur as hereinabove characterized consisting of breaking up the molten sulfur into relatively small particles and spraying the particles with water.

FRANK J. HILL.
